UNITED STATES PATENT OFFICE.

ANDREW BENDER, OF WASHINGTON, DISTRICT OF COLUMBIA.

SPRING-MOTOR.

SPECIFICATION forming part of Letters Patent No. 703,373, dated July 1, 1902.

Application filed October 12, 1901. Serial No. 78,455. (No model.)

To all whom it may concern:

Be it known that I, ANDREW BENDER, a citizen of the United States of America, and a resident of Washington, in the District of Columbia, have invented certain new and useful Improvements in Spring-Motors, of which the following is a specification.

My invention relates to certain new and useful improvements in spring-motors wherein two springs or sets of springs are employed to successively and alternately generate motion, the springs being automatically alternately thrown into engagement with the part to be driven and being held against unwinding when not in such engagement, proper mechanism being provided for winding up the springs when disengaged, the engagement of the springs with the winding mechanism being also automatic and simultaneous with their disengagement from the driving mechanism; and for this purpose it consists in the construction, arrangement, and combination of the several parts of which it is composed, as will be hereinafter more fully described and claimed.

Referring to the accompanying drawings, in which corresponding parts are designated by similar marks of reference, Figure 1 is a front elevation of a motor constructed in accordance with my present invention. Fig. 2 is a section thereof on the line X X.

The framework, which may be of any approved construction, is shown in the accompanying drawings as consisting of the side uprights A, cross-bar A', and braces A², the side uprights carrying the transverse axle 1. Mounted upon the axle 1 midway between the uprights is the hub 2, having thereon a gear-wheel 3, the ends of the hub being shouldered, as at 4, or otherwise cut away to form on each end one member of a clutch. Upon the axle and on each side of the hub is a sleeve 5, having its inner end, as at 6, suitably formed to engage the clutch member 4 upon the hub, while a clutch member 7 is also formed at the other end of each sleeve. Each sleeve has secured thereto one end of a spring 8, the opposite end of which is secured to the frame, and these springs when their respective sleeves are in clutch with the hub 2 drive the latter.

In order to wind up the sleeves, a collar 9 is

mounted on each end of the axle 1 outside the sleeve 5, each collar having its inner end properly shaped to form a clutch member 9^a 55 to engage the corresponding outer end of the adjacent sleeve 5, the distance between the hub 2 and the collar 9 being slightly greater than the extreme length of the sleeve 5, so that while a sleeve may be engaged with 60 either the hub or a collar (for which purpose it is capable of longitudinal movement on the axle) it cannot simultaneously engage both.

Each collar 9 has a sprocket-wheel 10 and ratchet-teeth 11 thereon, the latter being engaged by spring-click 11', secured to the framework to prevent the rearward rotation of the collar.

Each of the sprocket-wheels 10 may have motion imparted thereto by a belt 11^a, passing thereover and over the corresponding wheels 12 upon the winding-shaft 13, carried in the upper ends of the uprights A, and which may be turned by means of the crank 13, and it will thus be seen that the spring which 75 may have its sleeve in engagement with one of the collars will be wound up and that this may be done while the hub 2 is being driven by the other spring, the spring after having been wound up and while in engagement with 80 the collar being prevented from unwinding by the click 11.

In order to permit the winding up of both springs and the driving of the hub by the springs alternately without requiring the attendance of the operator further than to wind up each spring after it has run down, I provide an automatic shifting device which as each spring runs down removes it from engagement with the hub and throws it into engagement with the corresponding collar 9 and at the same time removes the sleeve of the opposite spring out of engagement with its collar and places it in clutch with the hub, the first-named spring being then in a position to be rewound, if desired, by the operator while the hub is being driven by the last-named spring. This I accomplish by mounting in hangers 14 from the cross-bar A' a sliding rod 15, having pendent arms 16 on each end thereof, the lower end of each arm encircling the corresponding sleeve 5 upon the outside of the spring 8 thereof, so that as the rod 15 may be shifted from side to side the

described disengagement and reengagement of the hub, sleeves, and collars will be effected. To effect this shifting of the rod, I mount in a bracket 17, hung from the center 5 of the cross-bar A', a pinion 18, having an arm 19 extending therefrom, the free end of the arm being slotted, as at 19^a, to engage a pin 20 in a link 30, the ends of which are attached to the arms 16, while on each side of 10 the pinion 18 is pivoted in the bracket a lever 21, one end of which has a circular toothed face 21^a engaging with the pinion and the other end of which projects so as to be struck by the spring on the corresponding side when 15 the latter has unwound to a predetermined extent. As it is advisable that one spring be engaged with the central hub before the other one is disengaged therefrom, I hinge the arms 16 to the rod 15, as at 31, and place 20 banking-shoulders 32 on the rod, so that the arms 16 can be swung inwardly to a limited extent from their vertical position, but cannot be swung outwardly, and I connect the link 30 to said arms by pins 33, passing 25 through slots 34 in the link, the proportion of the slots being such that when the parts are in the position shown in Fig. 1, with the right-hand spring and driving mechanism in engagement with the central hub, a movement 30 of the link 30 to the right caused by the unwinding of the said spring will first cause the arm 16, shifting the left-hand spring mechanism, to turn slightly on its pivot, whereby the said coupling 6, shifted by the said left-hand arm, will be brought into engagement 35 with the corresponding clutch member of the central hub. Continued movement of the link brings the inner end of the slot on its right-hand end into engagement with the pin 33 on the right-hand arm, forcing that arm to the right, and with it the rod 15, the clutch governed by the right-hand arm being thus 40 disengaged from the central hub. It will be thus seen that when one of the springs has 45 been thus unwound it will strike the end of the corresponding lever, forcing it up, turning the pinion, and with it its arms 19, toward the corresponding side of the frame by which the rod 15 will be shifted, thus shifting 50 the two sleeves in the manner described, whereby the other spring will be placed in engagement to drive the machine, during which time the first-named spring may be rewound to be in turn automatically thrown 55 into engagement.

A train of gear-wheels 22 is shown as gearing with the wheel 3 in order to increase the angular velocity of revolution, and of course this gearing may be adapted to the circumstances and use of the motor, and I prefer to place a click 40 in the train of gearing in order to permit the last wheel of the train to run by momentum when power from the driving-spring is cut off or reduced.

65 The speed of rotation of the wheel may be governed by a brake. I have shown such a brake consisting of arms 23, pivoted at 23^a in

the downward extension 17^b of the bracket 17, the lower ends of the arms having brake-shoes 23^b upon the opposite sides of the wheel, 70 the upper ends of the arms being adapted to be forced apart by the toggle-levers 24, actuated by the connecting-rod 25 from a lever 26, the position of which may be varied from time to time by the operator, according to 75 the speed at which it is desired that the wheel be driven.

Having thus described my invention, what I claim, and desire to secure by Letters Patent of the United States, is—

1. In a spring-motor, the combination with a driven wheel, of two springs, a clutch connecting the driven wheel with each spring, levers, each of which is adapted to be struck by a corresponding spring when unwound to 85 a predetermined extent, and means actuated by each lever to throw that spring out of clutch with the wheel and the other spring into clutch therewith, whereby the springs are alternately disengaged from the driving-wheel, and means whereby the spring may be wound when so disengaged, substantially as described.

2. In a spring-motor, the combination with a wheel, of a collar and a longitudinally-movable sleeve on each side of the wheel, the sleeves being interposed between the wheel and collars and being adapted to be clutched to either, a driving-spring secured to each sleeve, a common axle upon which the wheel 100 is mounted and the collars and sleeves rotate, and means whereby each sleeve is automatically longitudinally moved upon the axle, and the springs are alternately thrown into clutch with the wheel and released from the corresponding collar, and released from the wheel 105 and clutched with corresponding collar, substantially as described.

3. In a spring-motor, the combination with a wheel, having each of the ends of its hubs 110 shouldered to form one member of a clutch, of a collar having its one end shouldered to form one member of a clutch and a longitudinally-movable sleeve, each end of each of the sleeves being slotted to form one member 115 of a clutch on each side of the wheel, the sleeves being interposed between the wheel and collars and being adapted to be clutched to either, a driving-spring secured to each sleeve, means for rotating the said collars to 120 wind up the springs, a common axle upon which the wheel is mounted and the collars and sleeves rotate, and means whereby each sleeve is automatically longitudinally moved upon the axle, whereby it is successively 125 thrown into clutch with the wheel and released from the corresponding collar, and released from the wheel and clutched with the corresponding collar, substantially as described.

4. In a spring-motor, the combination with a wheel, of a collar and a longitudinally-movable sleeve on each side of the wheel, the sleeves being interposed between the wheel

and collars, and being adapted to be clutched to either, a driving-spring secured to each sleeve, and means for rotating the said collars to wind up the springs, a common axle upon which the wheel is mounted and the collars and sleeves rotate, a sliding rod connected to the said sleeves, a pinion provided with an arm connected to the rod, and pivoted levers having circular rack-teeth upon their one ends engaging the said pinion, the opposite ends of the said levers being adapted to be struck by the spring when unwound to a predetermined extent and thus to shift the rod and the sleeves, substantially as described.

5 5. In a spring-motor, the combination with a driven wheel, a longitudinally-movable sleeve on each side thereof, adapted to be secured thereto, a spring secured to each sleeve, a sliding rod, having pivoted pendent arms, connecting the said sleeves, a link adapted to be thrown in one direction or the other by the unwinding of the several springs, and a slot-and-pin connection between the link and pendent arms, whereby the engagement of

said springs with the driven wheel may be 25 shifted and reshifted, the one spring engaging therewith before the other spring is released therefrom, substantially as described.

6. In a spring-motor the combination with a driven wheel, a longitudinally-movable sleeve 30 on each side thereof adapted to be secured thereto, a spring secured to each sleeve, pendent arms connected to the said sleeves, a lever adapted to be thrown in one direction or the other by the unwinding of the several 35 springs, and a loose connection between the lever and pendent arms, whereby the engagement of said springs with the driven wheel may be shifted and reshifted, the one spring engaging therewith before the other spring is 40 released therefrom, substantially as described.

Signed at Washington, District of Columbia, this 25th day of September, 1901.
